UNITED STATES PATENT OFFICE.

BENJAMIN MAYER, OF BALTIMORE, MARYLAND, ASSIGNOR TO THE BISIGHT COMPANY, OF BALTIMORE, MARYLAND, A CORPORATION OF MARYLAND.

BIFOCAL-LENS GRINDER.

1,181,471.

Specification of Letters Patent.

Patented May 2, 1916.

Application filed January 6, 1913. Serial No. 740,564.

To all whom it may concern:

Be it known that I, BENJAMIN MAYER, a citizen of the United States, residing at Baltimore, in the State of Maryland, have 5 invented certain new and useful Improvements in Bifocal-Lens Grinders, of which the following is a specification.

This invention relates to lens-grinding machines, and has especial reference to that 10 class of devices designed to grind or polish one-piece bifocal lenses.

The object of my invention is to provide a simple and inexpensive device adapted to 15 grind a glass-blank to a double lens-blank having a circular inner field of the particular curvature required of the near-vision portion of the lenses, and an encircling or outer field of the curvature required of the distance-vision portion of the lenses, the resulting blank being subsequently divided 20 and finished in the usual manner to produce two bifocal lenses.

The invention is illustrated in the accompanying drawings, wherein:

25 Figure 1 is a transverse vertical section of the grinding machine; Fig. 2 is a plan of the machine; and Fig. 3 is a plan of the bifocal side of the lens-blank, after the grinding is completed, ready for division into two 30 uncut lenses.

The apparatus illustrated comprises an emery-pan 1 of the usual type, mounted upon a table or other support 2. A shaft 3, adapted to be rotated by any suitable means, 35 as by a pulley 3', passes through the emery-pan 1, and is connected at its upper end with the lower side of a glass-blank holding-disk 4, which rotates with it. Within a pocket in the upper face of the disk 4 is cemented or 40 otherwise secured the glass-blank 4' which is to be ground. At suitable points on the table 2 are fixed two standards 5, which support a cross-bar 6. On this bar are slidably mounted two clamps 7, 7', of any suitable 45 form, receiving rods 8, 8', which can be adjusted and clamped at any desired angle in the vertical plane. As shown, these clamps 7, 7', comprise a vertically apertured portion 15, adapted to receive the rods 8, 8', snugly but adjustably, and a horizontally apertured portion 16, adapted to receive the threaded bolts 17, in such manner that upon tightening up the bolts, the portion 16 will

be securely held against the split-sleeves 18 adjustably mounted on the bar 6. The lower 55 ends of the rods 8, 8', enter pockets 9, 9' in the grinding-disks 10, 10', and hold them in contact with the inner and outer portions, respectively, of the upper surface of the glass-blank 4', in such position as to 60 grind the desired curvatures thereon. The grinding disks are free to rotate, and do rotate, about their own axes, thus bringing the whole surface of the disks into constantly varying contact with the lens surface, thereby avoiding all streaks or striations in the lens surface. The grinding disk 10 is somewhat smaller than the disk 10', and grinds the central smaller near-vision portion, while disk 10' grinds the larger annular 70 distance-field.

In using my device, the glass-blank 4' is secured in the disk 4; the rod 8 is adjusted by means of the clamp 7 so that the smaller grinding disk 10 is held nearly upon the 75 center of the blank 4', its exact location being determined by the required size of the near-vision portion; and the rod 8' is adjusted by means of the clamp 7' so that the larger grinding-disk 10' is held in contact 80 with the blank outside of the circular area traversed by the smaller grinding-disk. As the shaft 3 rotates, carrying with it the disk 4 and the blank 4', emery being supplied to the grinders, the inner or central portion 85 of the blank is ground by disk 10 to one curvature 12, Fig. 3, determined by the adjustment of rod 8; and the outer portion will be ground by disk 10' to the desired 90 curvature 13 of the distance-field, determined by the adjustment of rod 8'. When the grinding is completed, the blank is divided along the line A—B, thus producing 95 two bifocal lens-blanks. By the use of this machine, a bifocal lens can be produced having either a definite dividing line or an invisible merger between the two fields of vision. By covering the faces of the disks 10 and 10' with cloth or like material, the machine may be used for polishing the lens-blank, rouge being supplied.

I claim:

A one-piece bifocal-lens grinding-machine, comprising a revoluble blank-support, a near-vision grinder, a distance-field 105 grinder, a cross-bar mounted above said

blank-support, rods carried by said cross-bar and holding said grinders in contact respectively with the central and outer portions of the blanks, said grinders being free to 5 rotate on their own axes, and means for adjusting the positions of said rods and grinders to produce the desired curvatures.

In testimony whereof I affix my signature in presence of two witnesses.

BENJAMIN MAYER.
